UNITED STATES PATENT OFFICE.

LEONIDAS MORIN, OF MANCHESTER, NEW HAMPSHIRE.

STOP-MOTION FOR KNITTING-MACHINES.

1,323,087.

Specification of Letters Patent. Patented Nov. 25, 1919.

Application filed July 18, 1917. Serial No. 181,402.

To all whom it may concern:

Be it known that I, LEONIDAS MORIN, a citizen of the United States, residing at Manchester, in the county of Hillsborough 5 and State of New Hampshire, have invented new and useful Improvements in Stop-Motions for Knitting-Machines, of which the following is a specification.

This invention relates to stop motions for 10 knitting machines, and one of the objects is to provide a sufficient length of thread when the latter fails to feed properly from the bobbin, with means for releasing that portion of the thread being fed, whereby time 15 is afforded for stopping the machine automatically before the thread breaks.

A further object is to provide for stopping the machine automatically when the 20 thread on the bobbin or cone is exhausted, by placing in operation certain elements of the mechanism serving to stop the machine under the circumstances first mentioned.

A further object is to provide in a stop motion of the character indicated an upper 25 series of arms normally holding the disengaging apparatus out of operation, but automatically operated when undue tension is placed on the thread, and a lower series of arms placed in operation when the thread 30 fails because of exhausting the bobbin or cone, at which time certain thread supported devices are released by dropping the thread.

A still further object is to provide a device 35 which may readily be rethreaded without loss of time and which shall be simple in construction and unusually effective in operation.

With the foregoing and other objects in 40 view, the invention consists in the novel construction, combination and arrangement of elements hereinafter described and claimed.

Figure 1 is a view of the device in side 45 elevation.

Fig. 2 is a view in vertical section.

Fig. 3 is a further view in vertical section, looking from another direction.

Fig. 4 is a horizontal section on line 4-4 50 of Fig. 2.

Fig. 5 is a horizontal section on line 5-5 of Fig. 2.

Fig. 6 is a fragmentary view in vertical section showing the movement of certain of 55 the elements illustrated in Figs. 1 and 2.

In the drawings I have illustrated a de-

vice including four arms for carrying the threads but it will be understood that any suitable number of arms may be employed. The proportions of the construction illustrated are such that eight arms may be provided instead of four as shown. The device is mounted about four or five feet above the knitting machine and includes an outer casing 10 carried upon a base 12 which is supported on a standard 14, said base 12 being provided with a socket member 15 into which is threaded a bolt or set screw 16 adapted to engage the upper end of the standard and hold the mechanism in proper 60 position.

The manner of connecting the stop motion with the knitting machine proper may vary to a certain extent depending upon the type of machine with which the stop motion 75 is to be used. I have shown conventionally a standard or member 18 on which is mounted a bell crank lever 19 pivoted at the point 20 and having its lower end connected with a bar 21 which may be slotted at one 80 end as at 22 for connection with devices leading to the knitting machine proper. Bell crank lever 19 has pivotal and adjustable connection with a vertically extending rod 23 which is adapted to engage any of the apertures 24 in said lever. This rod 23 is connected with a vertically slidable bar 25 forming a portion of the stop motion proper and which will be referred to more 85 particularly in the following description.

The thread from the bobbin or cone is designated 30 and passes through an eye slide formed of loped wire and designated 31, this thread guiding member being supported by the end of arm 32 pivoted at 33 95 to a bracket 34 carried upon the upper and outer portion of the casing. This arm 32 extends inwardly toward the center of the casing 10 and is held in normal position by means of a spring 36 connected with an annular member or ring 37 mounted on the inner side of the casing and supported therein by means of brackets 38 passing through slots 39 in the casing, said devices 38 being engaged by screws passing into the wall of the casing. This ring 37 provides 100 means for securing the ends of the spring 36 connected with certain of the arms 32. Other arms 32 may be connected by means of similar springs 36 with a ring 40 similarly mounted with reference to the casing. 105

The operation of arms 32 causes the ele-

vation of plate 43 carrying on its lower side a tubular member 44 which operates on a vertical guide 45 supported from a transverse bar 46 connected at its ends with the casing. The lower end of the guide is offset and limits the movement of the plate 43. This plate has connection by a wire or the like 47 with a latch 48 pivotally mounted at 49. This member 48 is notched 10 at the point 50 and engages the upper end of a trigger or the like having the form of a bell crank lever and designated 51, this device being pivotally mounted at the point 52 and having an offset end 53 15 which is engaged by a flat spring 54 tending to hold the lower end of the trigger upwardly. Element 51 projects under and engages an offset portion 54' on an angular arm 55, having the form of a bell crank lever and adapted for movement about its pivotal point 56. The lower arm of the bell crank lever is notched at 57 and the notched portion engages a pin 58 carried by vertically movable bar 25 controlling mechanism for 20 directly stopping the knitting machine. 25

Rigidly connected with vertically sliding bar 25 is a horizontally extending arm 60 provided with a hook portion 61, the arm extending transversely with reference to 30 a vertical stationary member 62 comprising a portion of the frame which mounts the operative elements just described. Connected with the lower end of bell crank lever 51 is a wire or the like designated 65 which passes 35 downwardly through the hook 61 and is adapted to engage or to be engaged by said hook.

The frame of which vertical member 62 forms a part also includes a horizontally extending member 66 on which the bell crank lever 51 is directly mounted at the point 52, and the latch 48 is mounted on upstanding member 67 projecting from transverse member 66. The frame further includes a main 40 vertical supporting plate 68 having a foot member or members 69 extending laterally from the lower end thereof and secured to the base 12 of the casing.

The vertically sliding member 25 is under 50 the influence of a coiled spring 70 secured at 71.

The thread 30 passing through members 31 passes thence to pivoted hooks 75 each passing through an aperture 76 in an arm 55 32, and the thread passes thence through a rack 77 and a fork 78, the thread serving to hold fork 78 and its arm 79 in an upper position under normal conditions. The release of fork 78 by the thread and the consequent 60 release of arm 79 causes the rack to move downwardly and outwardly, and the offset or crank portion 80 of the arm operates a radially extending arm or lever 81 which is fulcrumed at 82 in an annular member 83 mounted above the base plate 12. The out-

ward and downward movement of arm 79 depresses the outer end of the lever 81, elevating the inner end and also elevating a plate 84 adapted for movement in an upward direction and when so moved adapted to engage the transverse member 60 previously described. Plate 84 is provided with a tubular guiding member 85 operating upon vertical member 62 of the stationary frame. 70

The release of fork 78 and arm 79 by the 75 thread produces upward or disengaging movement of the latch 48 through the medium of connecting wire 87 secured to said latch at the point 88.

When the thread or yarn fails to feed 80 properly and tension is placed thereon, the thread pulls on the outer end of arm 32 and causes the hook 75 to move downwardly, thus freeing the thread and allowing it to slide over the upper and outer portion 77' of rack 85 77 allowing it to slip to the side so that it may escape the eye member 31 and furnish sufficient length of thread to permit the machine to be stopped without breaking said thread. 90

The downward pull on the outer end of lever 32 will elevate the plate 43 and will release the latch 48 as before indicated, thus freeing bell crank lever 51 and causing it to operate lever 54 and release vertical sliding bar 25. The upward movement of plate 84 by the operation of the lower stop motion mechanism, including the levers 81, causes a similar operation of the latch through the medium of connecting rod or wire 87. 95

Wire 87 has an offset 87' engaged by offset 86 on member 85 for producing the movement above indicated. 100

The arms 79 are raised to a position to permit rethreading when the plate 84 is depressed by the downward movement of bar 25 and transverse member 60. 105

What is claimed is:

1. In a stop motion for a knitting machine, a slidably mounted bar, operating 110 means connected with said bar and with the driving means of said machine, a pivotally mounted lever, an engaging device thereon for retaining the bar in a given position, means including a pivotally mounted latch 115 for controlling the movement of the lever, a plurality of pivotally mounted arms under the control of the thread supplied to the machine, and means operated by the arms for controlling the latch, a casing for housing certain of the operative elements specified, an adjustable annular member mounted within the casing, and springs connecting the annular member with the arms. 120

2. In a stop motion for a knitting machine, a slidably mounted bar, connecting means between the bar and the driving means for the machine, a pivotally mounted lever, means for controlling the operation 125 of the bar by said lever, a second pivotally 130

5 mounted lever engaging the lever first mentioned, a latch controlling the operation of the second lever, and a plurality of series of thread controlled members for controlling the operation of the latch, one of said series including a plurality of pivotally mounted arms, a casing with reference to which the arms are pivotally supported, adjustable annular members within the casing, and 10 springs connecting the annular members with the pivoted arms.

3. In a stop motion for a knitting machine, a plurality of pivotally mounted levers, certain of the arms of which are 15 adapted to engage, an engaging device carried by an arm of one of said levers, a slideable member adapted to contact with the engaging device, a latch controlling the operation of the other of said levers, and a plurality 20 of series of thread controlled arms for controlling the operation of the latch, one of said series including a plurality of pivotally mounted arms, a casing with reference to which the arms are pivotally supported, adjustable annular members within 25 the casing, and springs connecting the annular members with the pivoted arms.

4. In a stop motion for a knitting machine, a slideable bar, connecting means between the bar and the driving means for the machine, a plurality of pivotally mounted bell crank levers, certain of the arms of said levers being adapted to engage, a spring engaging an arm of one of said levers for moving the lever last named to operative position, a latch for controlling the position of the other of said levers, and independently operated means for controlling the position of the latch, said means last named including pivot and stationary thread guiding and retaining elements, the upper portion of the stationary elements being inclined,

independent pivoted spring-held arms and devices associated therewith for supporting a thread, the thread being released under 45 excessive tension and guided to a slack position by the inclined portions of the stationary elements.

5. In a stop motion, a plurality of pivotally mounted arms, a casing into which 50 the inner ends of the arms extend in a radial direction, an element engaged by the approaching ends of the several arms, means directly actuated by the element thus engaged for stopping the machine, a plurality 55 of looped members for supporting threads on the ends of said arms, a pivotally mounted hook projecting loosely through each arm for supporting the thread and adapted to release said thread upon the movement of 60 the arm on its pivot, and a thread guiding member mounted adjacent to said pivotally mounted hook and aiding in the release of a given length of thread passing from the thread supporting devices first mentioned 65 and thence to the knitting machine.

6. In a stop motion, a plurality of series of thread controlled arms, a reciprocable spring controlled member adapted for connection with the driving means of a knitting machine, means for holding said member in a position permitting the operation of the knitting device, independent means under the control of each series of arms for releasing said spring controlled member and 70 stopping the machine, said means last mentioned including a plurality of bell-crank levers operating in parallel planes and reversely mounted, one of the levers including an offset portion contacting with the 75 other lever.

In testimony whereof I affix my signature.

LEONIDAS MORIN.
